LOOM PICKER

Frank W. Merrick, Boston, Mass., assignor to
American Stay Company, East Boston, Mass.,
a corporation of Massachusetts

Application May 19, 1934, Serial No. 726,511

13 Claims. (Cl. 139—159)

My invention, which relates to loom pickers, and has among its objects the provision of a durable, readily replaceable bunter head, will be best understood from the following description when read in the light of the accompanying drawing of an embodiment of the invention, the scope of which will be more particularly pointed out in the appended claims.

In the drawing:—

Fig. 1 is an elevation of a loom picker constructed according to the invention;

Figs. 2, 3, and 4 are respectively a plan, front elevation and rear elevation of a loom picker according to Fig. 1;

Fig. 5 is a section on the line 5—5 of Fig. 2; Fig. 6 is a section on the line 6—6 of Fig. 1.

Fig. 7 is an elevation corresponding to Fig. 1 with the holder for the loom picker in open position;

Fig. 8 is a front and end elevation of a detail; and

Fig. 9 is a front and end elevation of another detail.

Referring to the drawing, the loom picker comprises a bunter head which, as illustrated, is formed of a plurality of laminations 1 of leather or other suitable material. As shown, the bunter head in transverse cross-section is elongated in the direction of the length of the stick, and preferably is oval-shaped in cross-section. In the present form of the invention, the bunter head is provided with a shuttle point receiving recess 3 of approximately conical shape, the laminations of the shuttle point engaging portion of the bunter head preferably being formed with appropriately shaped perforations so that when the laminations are assembled the conical-shaped recess will be formed.

It has been found that the bunter head tends to be deformed in a direction lengthwise of the stick much more than laterally of the stick, and that this deformation is greater toward either the top or bottom of the bunter head than in a transverse direction depending upon whether the bunter head engages the shuttle point before or after the picker stick passes through its vertical position. Commonly, the bunter head engages the shuttle point after the picker stick has moved to beyond its vertical position, and therefore the maximum tendency of deformation of the bunter head occurs at that portion thereof which is between the shuttle point engaging recess and the top of the bunter head. Applicant has found that under the last named conditions a more durable bunter head is provided by positioning the axis of the

shuttle point engaging recess 3 below the longitudinal axis of the bunter head, as clearly illustrated in Figs. 3 and 5. In cases where the bunter head engages the shuttle point before the picker stick has passed through its vertical position, in which case the tendency of the bunter head to be deformed is greatest below the shuttle point engaging recess, the bunter head shown in the drawing may be turned axially through 180° so that the shuttle point receiving recess is positioned above the axis of the bunter head.

As illustrated, the bunter head is provided with a metal holder comprising the upper and lower halves, each comprising a bunter head casing portion 5 having integrally formed therewith a pair of arms 7 which embrace the picker stick 9. At the rearward side of the stick is positioned a member 11 having oppositely projecting lugs 13 loosely fitting into perforations 15 at the ends of the respective arms 7. As shown, this member 11 is provided with a screw threaded perforation 17 which receives a screw 19, the latter being provided with a polygonal recess 21 for receiving a key wrench so that the screw may be turned. Between the end of the screw 19 and the picker stick 9 in the present form of the invention is provided a bearing plate 23 having a cup-shaped recess 25 for receiving the rounded end 27 of the screw. Conveniently, the plate 23 is provided at its upper edge with projecting lugs 24 which overlie the arms 7 so as to cause the plate to be retained in operative position when the screw is loosened and the parts are in their position shown by Fig. 7.

In the present form of the invention, the upper and lower halves of the casing portion 5 of the bunter head holder at their outer ends are provided with inturned lips 29 which engage with the upper and lower portions respectively of the end face of the bunter head. With this construction, by backing off on the screw 19 the halves of the bunter head holder may be readily spread apart to permit the insertion of the bunter head, the parts under these conditions being in the position shown by Fig. 7. By tightening the screw the halves of the bunter head holder may be held in closed position, as illustrated by Figs. 1, 3, 5, and 6, operatively to clamp the bunter head between the stick and the lips 29, the lateral walls of the casing portions 5 of the holder under these conditions bearing against the upper and lower portions of the lateral walls of the bunter head to position the latter and aid in resisting lateral deformation thereof.

As illustrated, between the bunter head and the stick is positioned a slightly curved spring 55

member 31 provided with punch pricks 33 to provide points 35 adapted to be forced into the material of the stick when the parts are in the positions shown by Figs. 1 and 5. This spring forms 5 a bearing plate for the bunter head, and aids the operator in maintaining the picker in predetermined position when the holder is loosened for replacing the bunter head. As its end portions are engaged by the edges of the casing portions 5 10 of the holder, it also acts to prevent any tendency of turning of the screw 19 when the loom is in operation, and in this sense provides a nut lock for said screw. Conveniently, the spring at its upper and lower edges is provided with lips 37 15 for engaging the adjacent edges of the portions 5 of the bunter head holder to minimize the tendency of the spring to fall when the parts are in the position shown by Fig. 7.

It will be observed that in the present construction the metallic casing for the bunter head is in substance longitudinally split so that it may be spread apart to enable replacement of the bunter head. In the absence of this construction, when a bunter head is to be replaced it is 25 necessary to remove the holder from the stick and have the holder so formed that the laminations may be inserted through the opening which normally receives the stick. Ordinarily it is necessary to replace only the shuttle point engaging 30 portion of the bunter head. With applicant's construction this may be readily accomplished and without removing all the laminations from the holder.

It will be understood that wide deviations may 35 be made from the embodiment of the invention described without departing from the spirit of the invention.

I claim:

1. A loom picker having, in combination, a 40 bunter head, and means for securing said bunter head to a picker stick comprising separable unconnected relatively movable portions for engaging with opposite lateral sides of said head and with the outer end face only thereof, said means 45 also comprising a picker stick embracing portion carrying means cooperating with said stick for drawing said portions and bunter head toward the stick.

2. A loom picker having, in combination, a 50 bunter head, and a device for operatively holding said bunter head against one side of a picker stick having a bunter head engaging portion and a picker stick embracing portion, said bunter head engaging portion being longitudinally split 55 and comprising relatively movable members which adjacent said head are unconnected rendering said bunter head engaging portion capable of being freely opened and closed for replacement of said head and having end portions for engaging with that end of said bunter head which is remote from said stick, said picker stick embracing portion comprising means operatively acting against that side of the stick which is opposite said bunter head for drawing said device in that 60 direction which will operatively clamp said bunter head between said stick and said end portions of said bunter head engaging portion of said device.

3. A loom picker having, in combination, a 70 bunter head arranged operatively to contact with a side of the picker stick, means for securing said bunter head to the picker stick comprising a plurality of relatively movable members which adjacent said head are unconnected and have 75 end portions for engaging with the outer end por-

tion of said head, a part to which said members are connected adapted to lie at the side of said stick opposite said head, and means acting to force said part away from said stick for holding said members in engagement with said head. 5

4. A loom picker having, in combination, a bunter head, means for securing said bunter head to a picker stick comprising a plurality of relatively movable members which adjacent said head are unconnected and have end portions for 10 engaging with the outer end portion of said head, a part to which said members are connected adapted to lie at the side of said stick opposite said head, and means cooperating with said part and said stick acting to force said part away from 15 said stick for causing said members to grip said head.

5. A loom picker having, in combination, a bunter head, means for securing said bunter head to a picker stick comprising a pair of members 20 formed to provide a bunter head holder, each of said members having arms adapted to lie at opposite sides of said stick, a member adapted to lie at the side of said stick opposite said bunter head, and means pivotally connecting said arms to the 25 last mentioned member.

6. A loom picker having, in combination, a bunter head, means for securing said bunter head to a picker stick comprising a pair of members 30 formed to provide a bunter head holder, each of said members having arms adapted to lie at opposite sides of said stick, a member adapted to lie at the side of said stick opposite said bunter head, means pivotally connecting said arms to the last 35 mentioned member for movement about a pivotal axis which lies in a plane including the longitudinal axis of said bunter head, and means cooperating with said last mentioned member and the stick for forcing said member away from the 40 stick. 40

7. A loom picker having, in combination, a bunter head, means for securing said bunter head to a picker stick comprising a pair of members 45 formed to provide a bunter head holder, each of said members having arms adapted to lie at opposite sides of said stick, a member adapted to lie at the side of said stick opposite said bunter head, means pivotally connecting said arms to the last 50 mentioned member for movement about a pivotal axis which lies in a plane including the longitudinal axis of said bunter head, a compression spring device between said head and the stick, and means cooperating with said last mentioned member and said stick for forcing said member 55 away from the stick. 55

8. A loom picker having means for securing a bunter head to the picker stick and operatively clamping it against a side of the stick comprising a bunter head holder having a portion for engaging with the lateral sides and with that end face of the bunter head which is remote from the stick and being open at the end thereof adjacent the stick, said holder comprising relatively movable parts which adjacent the bunter head are unconnected rendering said holder capable of being opened and closed for replacement of said head. 65

9. A loom picker having means for securing a bunter head to the picker stick and operatively clamping it against a side of the stick comprising 70 a bunter head holder having a portion for engaging with the lateral sides and with that end face of the bunter head which is remote from the stick and being open at the end thereof adjacent the stick, said holder comprising 75

hingedly connected relatively movable parts which adjacent the bunter head are unconnected rendering said holder capable of being opened and closed for replacement of said head.

5 10. A loom picker having, in combination, a bunter head having a shuttle point receiving cavity the axis of which is situated at one side of the longitudinal axis of the body portion of said head in a plane including the axis of the picker 10 stick, and a holder for said head comprising a pair of separable portions adapted to engage opposite sides of said head, said holder being so constructed as to engage the picker stick with said separable portions respectively situated at 15 the upper and lower sides of said head.

11. A loom picker having, in combination, a bunter head having a shuttle point receiving cavity the axis of which is situated below the longitudinal axis of the body portion of said head in 20 a plane including the axis of the picker stick, and a holder for said head comprising a pair of separable portions adapted to engage opposite sides of said head, said holder being so constructed as to engage the picker stick with said 25 separable portions respectively situated at the upper and lower sides of said head.

12. A loom picker having, in combination, a bunter head of elongated cross-section, a holder for said head for securing it to the picker stick with the longer dimension of said cross-section parallel to the axis of said stick, and a holder 5 for said head comprising a pair of separable portions adapted to engage opposite sides of said head, said holder being so constructed as to engage the picker stick with said separable portions respectively situated at the upper and lower sides 10 of said head.

13. A loom picker having, in combination, a bunter head of elongated cross-section, a holder for said head for securing it to the picker stick with the longer dimension of said cross-section 15 parallel to the axis of said stick, said head having a shuttle point receiving cavity the axis of which is at one side of the longitudinal axis of said head in a plane including the axis of said stick, and a holder for said head comprising a 20 pair of separable portions adapted to engage opposite sides of said head, said holder being so constructed as to engage the picker stick with said separable portions respectively situated at the upper and lower sides of said head. 25
